(57) **CLAIM**

The ornamental design for a LED light fixture, as shown and described.

DESCRIPTION

FIG. 1 is a perspective view of a LED light fixture showing our design;

FIG. 2 is another perspective view thereof;

FIG. 3 is a front elevation view thereof;

FIG. 4 is a rear elevation view thereof;

FIG. 5 is a left elevation view thereof, the right elevation view thereof being the same as the left;

FIG. 6 is a top plan view thereof; and,

FIG. 7 is a bottom plan view thereof.

The broken line showing is for the purpose of illustrating environmental structure and forms no part of the claimed design.
